ABSTRACT

Provided is a mattress that enables promoting breathing in a supine position. The mattress includes: a pair of ilium support portions arranged below respective parts conforming to at least widthwise outer portions of iliac crests of a pair of ilia of a pelvis for individually supporting parts conforming to the pair of ilia from below; and a sacrum adaptation portion arranged between the pair of ilium support portions and located below a sacrum between the pair of ilia of the pelvis. The pair of ilium support portions and the sacrum adaptation portion have such a configuration that a body pressure onto the sacrum adaptation portion is lower than a body pressure onto the pair of ilium support portions.

MAT

TECHNICAL FIELD

The present invention relates to a mattress, particularly to a mattress that enables promoting breathing in a supine position.

BACKGROUND ART

Some mattresses are used to support a body of a lying person. Such a kind of mattress is required to have a function of making a person lying thereon feel comfortable.

The comfortability of a mattress depends on a balance between a repulsive force of the mattress and a body pressure of the person lying on the mattress. The body pressure means a pressure given onto the mattress by the person lying on the mattress, and the distribution thereof varies according to the posture of the body. For example, in the supine position, the highest body pressure is at the buttock. In a case that the mattress supports the whole body of the person in the supine position, a mattress which uniformly has a strong repulsive force is likely to cause the body pressure to concentrate at the buttock and the back to thereby congest the buttock and the back. This consequently increases the roll-over to resolve the congestion, leading to a tendency of a light sleep. In contrast, a mattress which uniformly has a weak repulsive force causes the buttock to sink to a deepest level of the mattress. When being in the supine position, consequently, the spine greatly distorts from the S-shape in an upright position, which causes a lower-back pain and a stoop.

There have been known some mattresses whose repulsive force or surface shape is changed according to a location in a spinal direction of the person in the supine position to improve the comfortability (see, e.g., Patent Literatures 1 to 3). In these mattresses, regions with which the buttock and the back come into contact are set to be softer or lower than the other regions. Accordingly, the body pressure concentrated at the buttock and the back is distributed to other parts so that the mattress receives an almost uniform body pressure over the whole, and the spine in the supine position comes close to the S-shape in the upright position.

In addition to the number of times of the roll-over and the shape of the spine, the depth of the breathing is related to the comfortability. A deeper breathing during the sleeping makes the comfortability more excellent. However, even if the mattress receives the almost uniform body pressure over the whole as described above, the breathing may be likely to be shallow in the supine position. Thus, there is room for improvement in promoting the breathing.

SUMMARY OF INVENTION

The present invention has been made in view of the aforementioned circumstances, and an object thereof is to provide a mattress that enables promoting breathing in a supine position.

2

A mattress according to a present invention is adapted for supporting at least a part conforming to a pelvis of a person in a supine position, and includes: a pair of ilium support portions arranged below respective parts conforming to at least widthwise outer portions of iliac crests of a pair of ilia of the pelvis for individually supporting parts conforming to the pair of ilia from below; and a sacrum adaptation portion arranged between the pair of ilium support portions and located below a part conforming to a sacrum between the pair of ilia of the pelvis, wherein the pair of ilium support portions and the sacrum adaptation portion have such a configuration that a body pressure onto the sacrum adaptation portion is lower than a body pressure onto the pair of ilium support portions.

BRIEF DESCRIPTION OF DRAWINGS

FIG. 1 is a perspective view of a whole structure of a mattress according to an embodiment of the present invention.

FIG. 2 is a plan view of the mattress in FIG. 1.

FIG. 3 is a view of the mattress in a direction of an arrow A in FIG. 1.

FIG. 4 is an illustration showing a state in which a person is on the mattress in FIG. 1 in a supine position.

FIG. 5 is an underside view of the mattress and the person, schematically showing a relative positional relationship between the mattress in FIG. 1 and a skeleton of the person in the supine position.

FIG. 6 is a perspective view of a pelvis illustrating nutation of a sacrum.

FIG. 7 is a cross-sectional view schematically illustrating medial rotation of a pair of ilia and nutation of the sacrum of the person in the supine position on the mattress in FIG. 1.

FIG. 8 is a cross-sectional view illustrating a state of a part conforming to the sacrum of the person on the mattress in FIG. 1 in the supine position being supported by a sacrum support portion.

FIG. 9 is a cross-sectional view illustrating, as a modification of the invention, a state of a part conforming to the sacrum and a lumbar vertebra being supported by a placement surface of the sacrum support portion, the placement surface gradually lowering as advancing toward a leg.

FIG. 10 is a perspective view of a mattress which is another modification of the invention, and includes a sacrum adaptation portion having a sacrum non-support portion.

FIG. 11 is a perspective view of a mattress which is further another modification of the invention, and includes no back support portion.

DESCRIPTION OF EMBODIMENT

One preferable embodiment of the present invention will be described below with reference to the attached drawings.

Outline of Mattress 1

A mattress 1 shown in FIGS. 1 to 3 is integrally shaped into a thin rectangular cuboid and made of elastic material such as urethane, as an example. The mattress 1 constitutes a bed together with an unillustrated frame or a base supporting the mattress 1. The mattress 1 has such a size as to support the whole body of a person 50 thereon in the supine position on the whole upper surface thereof (see FIGS. 4 and 5). For example, the size of the mattress 1 is set to match a body shape of a normal adult (e.g., a Japanese adult male who is 170 cm tall and weighs 70 kg approximately). In the present invention, the mattress 1 may have a size enough to

support at least a part conforming to the pelvis PV of the person 50 in the supine position (see FIGS. 4 and 5).

Directions in the description and the drawings are defined as directions X (head-toward direction X1 and leg-toward direction X2) in which the body of the person 50 in the supine position extends, width directions Y (rightward direction Y1 and leftward direction Y2) of the person 50 in the supine position, and up-down directions Z (upward direction Z1 and downward direction Z2) of the mattress 1.

The mattress 1 has portions which protrude in the upward direction Z1 so as to come into contact with the back 52, the pelvis PV, and a leg of the person 50 in the supine position. Specifically, the mattress 1 includes: a base portion 2 whose shape is a flat rectangular cuboid; and three portions that protrude from an upper surface 2a of the base portion 2 in the upward direction Z1, in other words, a back support portion 3, a pelvis support portion 4, and a leg support portion 5. The back support portion 3 supports the back 52 of the person 50 in the supine position (see FIGS. 4 to 5). The pelvis support portion 4 is located away from the back support portion 3 in the leg-toward direction X2 and supports a part conforming to the pelvis PV (see FIGS. 4 to 5). The leg support portion 5 is located away from the pelvis support portion 4 in the leg-toward direction X2 and supports a part conforming to a portion in the vicinity of a femur FM of the leg (see FIGS. 4 to 5).

The mattress 1 has a head placement region 6 for permitting a placement of the head 51 away from the back support portion 3 in the head-toward direction X1 (see FIG. 4). The head placement region 6 has an exposed upper surface 2a of the base portion 2, on which a pillow P for supporting the head 51 is placed.

A hip joint placement region 7 is formed between the pelvis support portion 4 and the leg support portion 5 of the mattress 1, and has a space 7a over which a hip joint J2 is placed (see FIGS. 4 to 5). Since the hip joint J2 of the person 50 in the supine position is received in the space 7a and is not pressed by the mattress 1, the movement of a pair of hip bones HB in the width directions Y, which will be described later, is not hindered.

The pelvis support portion 4 (specifically, an ilium support portion 11, which will be described later) and the leg support portion 5 are squashed due to the weight of the person 50 in the supine position. However, the space 7a is not filled by the one in the supine position. Thus, the hip joint J2 is in a non-support state. The space 7a is set to have such a depth as not to be filled by the person 50 due to the weight. The pressure onto the hip joint 32 can be prevented by making the height of the hip joint placement region 7 identical to those of the pelvis support portion 4 and the leg support portion 5 and forming the hip joint placement region 7 of a material having a low hardness, instead of by forming the space 7a.

Description of Pelvis PV

The pelvis PV, which is supported by the pelvis support portion 4, will be described. As shown in FIGS. 4 to 6, the pelvis PV includes a pair of hip bones HB spaced away from each other in the width directions Y, a sacrum S located between the pair of hip bones HB, and a coccyx CC connected to an end portion of the sacrum S in the leg-toward direction X2.

The hip bone HB includes an ilium LM that forms a portion thereof in the head-toward direction X1, an arc-shaped pubis PB extending from an end portion of the ilium LM in the leg-toward direction X2 to the front (in the upward direction Z1 in FIG. 4) and the center of the body, and an arc-shaped ischium SN extending from the ilium LM

and curved in the leg-toward direction X2 to be connected with an end portion of the pubis PB closer to the center of the body. Each of the pair of ilia LM and the sacrum S are connected with each other by a sacroiliac joint J1.

As shown in FIGS. 4 to 6, the ilium LM is a curved, plate-like thin bone. The ilium LM includes an iliac crest LMa in an end portion thereof in the head-toward direction X1, which is an arc-shaped ridge portion curved outward in the width directions Y and forward (in the upward direction Z1 in FIG. 4) with respect to the body. In other words, the iliac crest LMa is an edge of the ilium LM closer to the head 51 (in the head-toward direction X1) of the person 50 in the supine position.

Detailed Description of Pelvis Support Portion 4

The pelvis support portion 4 in the embodiment has the following configuration to support the part conforming to the pelvis PV having the above-mentioned structure.

As shown in FIGS. 1 to 5, the pelvis support portion 4 includes a pair of ilium support portions 11 spaced away from each other in the width directions Y, and a sacrum support portion 12a arranged between the pair of ilium support portions 11. In the embodiment, the sacrum support portion 12a and the ilium support portions 11 on both sides thereof are separated by gaps 13 (see FIGS. 1 and 2). Thus, an effect of a body pressure onto the ilium support portion 11 on the sacrum S can be prevented, and nutation of the sacrum S which will be described later is not obstructed.

The pair of ilium support portions 11 is arranged at respective positions away from the iliac crests LMa of the pair of ilia LM of the pelvis PV in the downward direction Z2 so as to come into contact with parts conforming to at least outer portions LMb of the iliac crests LMa in the width directions Y (see FIG. 7). As shown in FIG. 7, the outer portion LMb of the iliac crest LMa in the width directions Y means a portion of the iliac crest LMa in the downward direction Z2 facing outward in the width directions Y. Thus, as shown in FIG. 7, the pair of ilium support portions 11 can individually support the parts conforming to the pair of ilia LM underneath Z2. Each ilium support portion 11 has a placement surface 11a over which the ilium LM is placed, an inner upper edge 11b that is an edge of the placement surface 11a closer to the center in the width directions Y of the mattress 1, and a leg side edge 11c that is an edge of the placement surface 11a in the leg-toward direction X2.

The placement surface 11a has a shape of a rectangle in a plan view, which has the same height as an upper surface of the back support portion 3 and is continuous with the upper surface. The placement surface 11a may be higher than the upper surface of the back support portion 3.

The placement surface 11a is set to have such a size as to come into contact with the part conforming to at least the outer portion of the iliac crest LMa in the width directions Y of a Japanese adult male, i.e., the part conforming to the widthwise outer portion LMb (see FIG. 7) of the iliac crest LMa but as not to come into contact with parts conforming to the pubis PB and the ischium SN. In this regard, as shown in FIG. 2, in a case that the interval I between the pair of ilium support portions 11 is set to be about 20 cm (e.g., 15 to 25 cm), the width II (length in the width directions Y) of the placement surface 11a is set to be 9 cm or more, and the depth III (length in longitudinal directions X) thereof is set to be about 11.5 cm (e.g., 10 to 15 cm).

The sacrum adaptation portion 12 is arranged between the pair of ilium support portions 11, and is located away in the downward direction Z2 from a part conforming to the sacrum S between the pair of ilia LM of the pelvis PV. As shown in FIGS. 1, 2, and 8, the sacrum adaptation portion 12

includes a sacrum support portion **12a** having a height **H2** lower than a height **H1** (see FIG. 3) of the ilium support portion **11** for supporting a part conforming to a portion **S1** of the sacrum **S** in the head-toward direction **X1** of the person **50** in the supine position, and a sacrum non-support portion **12b** having a height lower than the height **H2** of the sacrum support portion **12a** and spaced away in the downward direction **Z2** from a portion **S2** of the sacrum **S** in the leg-toward direction **X2** to render non-support to a part conforming to the portion **S2** in the leg-toward direction **X2**.

The sacrum support portion **12a** supports the part conforming to the portion **S1** of the sacrum **S** in the head-toward direction **X1** of the person in the supine position underneath **Z2**. The sacrum support portion **12a** has a placement surface **12a1** on which a part conforming to the sacrum **S** is placed and a leg side edge **12a2**, which is an edge of the placement surface **12a1** in the leg-toward direction **X2**.

The placement surface **12a1** has a shape of a rectangular and horizontally flat plane in a plan view, which is lower than the placement surface **11a** of the ilium support portion **11** and the upper surface of the back support portion **3**. For example, the placement surface **12a1** is set to have such a size as to come into contact with at least the part conforming to the portion **S1** of the sacrum **S** in the head-toward direction **X1** of a Japanese adult male but as not to come into contact with the part conforming to the ilium **LM**. In this case, for example, as shown in FIG. 2, the width **IV** (length in the width directions **Y**) of the placement surface **12a1** is set to be about 8 to 10 cm and the depth **V** (length in the longitudinal directions **X**) thereof is set to be about 8 to 12 cm (and smaller than the depth **III** of the placement surface **11a**). The depth **V** is preferably set to be about 6 to 12 cm.

The sacrum non-support portion **12b** renders non-support to the part conforming to the portion **S2** of the sacrum **S** in the leg-toward direction **X2**. The sacrum non-support portion **12b** is a plane located lower than the placement surface **12a1** of the sacrum support portion **12a** and away from the leg side edge **12a2** in the leg-toward direction **X2**. The sacrum non-support portion **12b** in the embodiment has the same height as the upper surface **2a** of the base portion **2**, but may be higher than the upper surface **2a** unless the sacrum non-support portion **12b** comes into contact with the part conforming to the portion **S2** of the sacrum **S** in the leg-toward direction **X2**. The sacrum non-support portion **12b** in the invention is supposed to give no body pressure onto the sacrum non-support portion **12b** in a case that the person **50** in the supine position has a normal body shape and weight. However, a heavy person may sink into the mattress **1**; in this case, the sacrum non-support portion **12b** may give a slight body pressure onto the sacrum non-support portion **12b** onto the part conforming to the sacrum. Also in this case, the body pressure onto the sacrum non-support portion **12b** is still lower than the body pressure onto the ilium support portion **11**.

The pair of ilium support portions **11** and the sacrum adaptation portion **12** have such a configuration that the body pressure onto the sacrum adaptation portion **12** onto the part conforming to the sacrum **S** of the person **50** in the supine position is lower than the body pressures from the pair of ilium support portions **11** onto the parts conforming to the pair of ilia **LM** of the person **50** in the supine position. In the embodiment, a relative height difference is made between the ilium support portion **11** and the sacrum support portion **12a** to reduce the body pressure onto the sacrum support portion **12a** partially. In this regard, the body pressure onto the sacrum support portion **12a** may be reduced partially by differentiating the hardness between the ilium

support portion **11** and the sacrum support portion **12a**, as in a modification described later. Further, a configuration as in a modification (see FIG. 10) described later, in which the whole of the sacrum adaptation portion **12** includes a sacrum non-support portion **12b** that renders non-support to the sacrum **S**, may allow the body pressure onto the sacrum adaptation portion **12** (i.e., the sacrum non-support portion **12b**) to be zero. In other words, the body pressure onto the sacrum adaptation portion **12** can be zero in the invention.

The respective body pressures from the ilium support portion **11** and the sacrum adaptation portion **12** are measured with, e.g., an existing body pressure measuring instrument. The body pressure measuring instrument determines a load on each divisional cell of a matrix of the region on the mattress **1** as the body pressure. With the body pressure measuring instrument, each body pressure onto the ilium support portion **11** and the sacrum support portion **12a** can be determined as the average value of the body pressure onto the ilium support portion **11** onto the region of the part conforming to the iliac crest **LMa** and the average value of the body pressure onto the sacrum adaptation portion **12** onto the region of the part conforming to the sacrum **S**.

In a specific case that a relative height difference is made between the ilium support portion **11** and the sacrum support portion **12a**, the height **H1** of the ilium support portion **11** is set to be greater than the height **H2** of the sacrum support portion **12a**, as shown in FIG. 3. The height **H1** of the ilium support portion **11** with respect to the upper surface **2a** of the base portion **2** is set to be, for example, about 5 mm to 4 cm, preferably about 2 cm, in accordance with the hardness of the mattress. In a case that the height **H1** of the ilium support portion **11** is less than 5 mm, the effect of supporting the outer portion **LMb** of the iliac crest **LMa** in the width directions **Y** cannot be obtained; on the other hand, in a case that the height **H1** is greater than 4 cm, the ilium support portion **11** protrudes too far from the back support portion **3** of the mattress **1**, which causes a problem such as discomfort. In order to resolve these problems, the height **H1** of the ilium support portion **11** is preferably set to be about 5 mm to 4 cm as described above.

In the embodiment, the height of the back support portion **3** and that of the leg support portion **5** are set to be the same as the height of the ilium support portion **11**, but the invention is not limited thereto. The height of the ilium support portion **11** may be set to be greater than those of the back support portion **3** and the leg support portion **5**.

The height **H2** of the sacrum support portion **12a** is set such that it can support the part conforming to the sacrum **S** so that the body pressure onto the sacrum support portion **12a** onto the part conforming to the sacrum **S** is lower than the body pressure onto the ilium support portion **11** onto the part conforming to the ilium **LM**. Specifically, the height **H2** of the sacrum support portion **12a** is set to be lower than the height **H1** of the pair of ilium support portions **11** and so that the sacrum support portion **12a** can come into contact with the part conforming to the sacrum **S** as shown in FIG. 8; for example, the height **H2** is set to be about 1 cm. The height **H2** of the sacrum support portion **12a** may be to such an extent that at least a part of the sacrum support portion **12a**, specifically, the leg side edge **12a2** can come into contact with the part conforming to the sacrum **S**.

Description of Relationship Between Exhalation and Nutation of Sacrum S

The present inventor has made eager studies on the tendency toward shallow breathing in the supine position, found that the breathing in the supine position is affected by obstruction of nutation of the sacrum in the supine position,

and made research to remove a factor of the obstruction of the nutation of the sacrum as described below.

For the breathing during the sleeping, which is an unconscious natural breathing, it is important how abundantly the natural breathing is performed. For the breathing, exhalation (breathing out) is important, and how much one exhales is deeply related to an amount of an inhalation. A deep exhalation allows much inhalation in accordance with the amount of the exhalation. A deep natural breathing during the sleeping prevents the blood oxygen level from lowering. An abundant exhalation makes the vagus nerve dominant, leading to a good sleep.

The exhalation can be promoted by facilitating movement of a diaphragm DP in the head-toward direction X1 to contract a rib cage RC shown in FIG. 5. The diaphragm DP is a muscular membrane that closes a lower end of the rib cage RC. The diaphragm DP has a shape of a dome protruding in the head-toward direction X1, which is in the dome shape when relaxed (in exhaling) and becomes flat with a center portion thereof moving in the leg-toward direction X2 when tensed (in inhaling). The diaphragm DP is connected to the vicinity of the second lumbar vertebra L2 continued to the sacrum S, specifically, connected to the lumbar vertebrae L1 to L3. When the sacrum S shown in FIGS. 4 to 7 nutates, i.e., tilts forward with respect to the person 50 (in the same direction as the upward direction Z1 in FIG. 4), the lumbar vertebrae L1 to L5 connected to the sacrum S move forward, facilitating relaxing of the diaphragm DP in the dome shape connected to the lumbar vertebrae L1 to L3 accordingly. This facilitates the movement of the diaphragm DP in the head-toward direction X1. Thus, the exhalation is promoted.

Since the sacroiliac joints J1 that connect the sacrum S and the pair of ilia LM are surrounded by many strong ligaments, the sacrum S cannot move independently. Therefore, the present inventor thought of promoting the nutation of the sacrum S utilizing the linked movement of the pair of ilia LM and the sacrum S.

As shown in FIG. 6, when the sacrum S nutates, a force is applied to each ilium LM of the pair of hip bones HB, so that the outer portion LMB of the iliac crest LMA in the width directions Y, which is the end portion of the ilium LM in the head-toward direction X1, moves forward with respect to the body (in the same direction as the upward direction Z1 in FIG. 4). Thus, the pair of ilia LM moves in such directions as to close inward (toward the center of the body), which provides a gap or play at the sacroiliac joint J1 to facilitate the movement of the sacrum S. In this regard, a sacral promontory Sa, which is an end portion of the sacrum S in the head-toward direction X1, moves forward (in the same direction as the upward direction Z1 in FIG. 4), and a portion of the sacrum S in the leg-toward direction X2 moves rearward (in the same direction as the downward direction Z2 in FIG. 4), enabling the whole of the sacrum S to smoothly nutate forward (in the direction Z1). A broader nutation of the sacrum S relaxes the diaphragm DP connected to the vicinity of the second lumbar vertebra L2 (from L1 to L3) so as to facilitate the movement thereof in the head-toward direction X1, which makes the breathing abundant. In this regard, the contraction of a lower portion of the rib cage RC for the exhalation becomes abundant.

The mattress 1 in the embodiment removes the obstruction of the nutation of the sacrum S due to the pressure of the mattress 1 onto the sacrum S in the supine position. Consequently, a movable range of the sacrum S can be extended.

As shown in FIG. 6, when the sacrum S nutates, the ilia LM of the hip bones HB move inward in the width directions

Y. Thus, the space between the pair of ilia LM becomes narrower, increasing the pressure in the abdominal cavity. This further facilitates the movement of the diaphragm DP in the head-toward direction X1. The pubis PB and the ischium SN, which are the portions of the hip bones HB other than the ilia LM, moves outward in the width directions Y (i.e., in directions along which the pubic symphysis PBA in FIG. 7 is opened).

On the other hand, after the nutation of the sacrum S and the exhalation for a while, the sacrum S performs counter-nutation, which is a counter action of the nutation. In the counternutation of the sacrum S, the sacral promontory Sa of the sacrum S in the head-toward direction X1 moves rearward (in the same direction as the downward direction Z2 in FIG. 4), and the portion of the sacrum S in the leg-toward direction X2 moves forward (in the same direction as the upward direction Z1 in FIG. 4). A counternutation of the sacrum S causes the diaphragm DP connected to the vicinity of the second lumbar vertebra L2 (from L1 to L3) to move in the leg-toward direction X2, causing the rib cage RC to expand. This allows much inhalation.

Features of Embodiment

(1) The present inventor has repeatedly made eager studies on promoting the breathing in the supine position with focusing on the movement of the pelvis PV as described above, to find that promoting the nutation of the sacrum S located between the pair of ilia LM of the pelvis PV tilting forward (in the same direction as the upward direction Z1 in FIG. 4) leads to promoting the breathing, achieving the invention of the mattress 1 having the configuration above.

A generally uniformly flat mattress gives body pressure onto both the ilium LM and the sacrum S in the supine position; particularly, the sacrum S is likely to receive a higher body pressure. In this case, the nutation of the sacrum S is obstructed and the breathing is not promoted.

In contrast, the mattress 1 in the embodiment includes the ilium support portion 11 as described above, and the height of the sacrum support portion 12a in the up-down directions Z is set to be lower than that of the ilium support portion 11. Therefore, the body pressure onto the sacrum support portion 12a becomes lower than the body pressure onto the ilium support portion 11. Thus, the sacrum S can smoothly nutate.

Additionally, a lowered body pressure onto the sacrum support portion 12a makes a relatively increased body pressure onto the ilium support portion 11. Thus, the sacroiliac joint J1 is opened while the outer portions LMB of the iliac crests LMA of the pair of ilia LM are pressed in closing directions (toward the center of the body in the width directions Y). Accordingly, the nutation of the sacrum S is promoted. Therefore, the sacrum S smoothly nutates even in the supine position, enabling the deep breathing during the sleeping to thereby improve the comfortability.

In other words, in order to promote the nutation of the sacrum S, as shown in FIGS. 1 to 5, the mattress 1 in the embodiment includes: the pair of ilium support portions 11 arranged at respective positions away from the iliac crests LMA, which are edges closer to the head of the person 50 (in the head-toward direction X1) in the supine position, of the pair of ilia LM of the pelvis PV in the downward direction Z2 so as to come into contact with parts conforming to at least outer portions LMB of the iliac crests LMA in the width directions Y; and the sacrum adaptation portion 12 including

the sacrum support portion **12a** and the sacrum non-support portion **12b** arranged between the pair of the ilium support portions **11**.

Thus, as shown in FIGS. 4, 5, and 7, when the person **50** is in the supine position on the mattress **1** having the configuration above, the pair of ilium support portions **11** (specifically, the inner upper edges **11b** of the ilium support portions **11** and the portions therearound) can individually support the parts conforming to the pair of ilia LM underneath Z2 with coming into contact with the respective parts conforming to the iliac crests LMa of the pair of ilia LM. At this time, the pair of ilia LM receives a reaction force (body pressure) from the ilium support portions **11** on the parts conforming to the iliac crests LMa, which promotes the movement of turning forward (in the same direction as the upward direction Z1) and toward the center in the width directions Y with respect to the body (i.e., rotating medially).

In the mattress **1** above, the pair of ilium support portions **11** and the sacrum adaptation portion **12** (i.e., the sacrum support portion **12a** and the sacrum non-support portion **12b**) have such a configuration that the body pressure onto the sacrum adaptation portion **12** onto the part conforming to the sacrum **S** of the person **50** in the supine position is lower than the body pressure onto the pair of ilium support portions **11** onto the parts conforming to the pair of ilia LM of the person **50** in the supine position. Thus, the sacrum **S** between the pair of ilia LM can turn forward (in the same direction as the upward direction Z1) and in the leg-toward direction X2 in accordance with the medial rotation of the pair of ilia LM, i.e., can nutate, without being obstructed by the reaction force (body pressure) from the sacrum adaptation portion **12**.

In the nutation of the sacrum **S**, as described above and as shown in FIGS. 6 and 7, the sacral promontory **Sa**, which is the end portion of the sacrum **S** in the head-toward direction X1, moves forward (in the same direction as the upward direction Z1 in FIG. 4), and the portion of the sacrum **S** in the leg-toward direction X2 moves rearward (in the same direction as the downward direction Z2 in FIG. 4). Thus, the whole of the sacrum **S** nutates forward (in the direction Z1). In this regard, FIG. 7 shows a state just before the nutation of the sacrum **S**; FIG. 8 shows a state after the nutation of the sacrum **S**, in which the part conforming to the sacrum **S** comes into contact with the leg side edge **12a2** of the placement surface **12a1** of the sacrum support portion **12a** and the portions therearound.

The nutation of the sacrum **S** causes the diaphragm DP connected to the lumbar vertebrae L1 to L3 in the vicinity of the second lumbar vertebra L2 continued to the sacrum **S** to move in the direction X1 toward the head of the person **50** in the supine position (see FIG. 5). This makes the rib cage RC contract, thereby facilitating the exhalation. When the exhalation is facilitated, the inhalation, which is the counter action thereof, is also facilitated. Consequently, the breathing in the supine position can be promoted.

A normal evenly flat mattress on the market supports the part conforming to the sacrum **S** so that the part receives the same body pressure as the body pressure that the parts conforming to the ilia LM on both sides thereof receive. Thus, the sacroiliac joints J1 that connect the sacrum **S** with the ilia LM on both sides thereof are not relaxed. Therefore, the sacrum **S** cannot tilt forward with respect to the ilia LM, i.e., cannot nutate. On the other hand, in the mattress **1** in the embodiment, since the body pressure that the parts conforming to the pair of ilia LM receives and the body pressure that the part conforming to the sacrum **S** receives are made different from each other, the sacrum **S** can smoothly nutate.

(2) The mattress **1** in the embodiment is integrally made of a single material such as urethane, and the height H1 of the ilium support portion **11** is set to be greater than the height H2 of the sacrum support portion **12a** of the sacrum adaptation portion **12** as shown in FIG. 3. In this configuration, the ilium support portion **11** can reliably support the part conforming to the ilium LM to promote the medial rotation of the ilium LM and the nutation of the sacrum **S**, while reducing the reaction force (body pressure) from the sacrum support portion **12a** onto the part conforming to the sacrum **S**. Consequently, the breathing in the supine position can be reliably promoted.

(3) The mattress **1** in the embodiment includes the back support portion **3** that supports the back **52** of the person **50** in the supine position. The height of the back support portion **3** is set to be the same as that of the ilium support portion **11**. In this configuration, the mattress **1** supports the back **52** and the part conforming to the ilium LM of the person **50** in the supine position on the same plane. Thus, the discomfort due to the ilium support portion **11** protruding in the upward direction Z1 can be reduced.

(4) The sacrum adaptation portion **12** of the mattress **1** in the embodiment includes: the sacrum support portion **12a** having the height H2 lower than the height H1 of the ilium support portion **11** for supporting the part conforming to the portion S1 of the sacrum **S** in the head-toward direction X1 of the person **50** in the supine position, and the sacrum non-support portion **12b** having the height lower than the height H2 of the sacrum support portion **12a** and spaced away in the downward direction Z2 from the portion S2 of the sacrum **S** in the leg-toward direction X2 of the person **50** in the supine position to render non-support to the part conforming to the portion S2 in the leg-toward direction X2.

After the nutation of the sacrum **S**, the portion S1 of the sacrum **S** in the head-toward direction X1 is located away in the upward direction Z1 from the portion S2 thereof in the leg-toward direction X2. Therefore, in the configuration above, the sacrum support portion **12a** partially supports the part conforming to the portion S1 of the sacrum **S** in the head-toward direction X1, and the sacrum non-support portion **12b**, which is spaced away from the portion S2 in the downward direction Z2, renders non-support to the part conforming to the portion S2 in the leg-toward direction X2. This enables adjusting the body pressure onto the ilium support portion **11**, the body pressure onto the sacrum support portion **12a**, and the body pressure onto the sacrum non-support portion **12b** so as to gradually lower one after another in this order. Additionally, it is possible to further lower the average body pressure onto the sacrum **S** from the whole of the sacrum adaptation portion **12** with keeping the sacrum **S** tilting forward. This can promote a smooth nutation of the sacrum **S**. Consequently, the breathing in the supine position can be more reliably promoted.

(5) In the mattress **1** in the embodiment, the height H2 of the sacrum support portion **12a** is set such that it can support the sacrum **S** so that the body pressure onto the sacrum support portion **12a** onto the part conforming to the sacrum **S** is lower than the body pressure onto the ilium support portion **11** onto the part conforming to the ilium LM, as shown in FIG. 8.

This configuration eases the visible positioning. Further, the adjustment of the body pressure by height enables estimation of the body pressure in manufacturing a mattress, thereby easing the product management. The sacrum sup-

11

port portion **12a** can support the sacrum **S** so that it can nutate. Consequently, a load on the lumbar vertebrae L3 to L5 connected to the sacrum **S** can be reduced.

(6) In the embodiment, as shown in FIGS. 1 to 5, the hip joint placement region **7** is formed between the ilium support portion **11** of the pelvis support portion **4** and the leg support portion **5**. The hip joint placement region **7** has the space **7a** over which the hip joint **J2** is placed (see FIGS. 4 to 5). Thus, the hip joint **J2** of the person **50** in the supine position is received in the space **7a** and is not pressed by the mattress **1**. Accordingly, the movement of the pair of hip bones **HB** in the width directions **Y** is not hindered. Therefore, the hip joint **J2** is not restrained, which allows the ilium **LM** to smoothly rotate medially and the sacrum **S** to smoothly nutate. Consequently, the breathing can be promoted. Over the hip joint placement region **7** in FIG. 5, the lower portion of the ilium **LM** and the upper portion of the ischium **SN** of the hip bone **HB** are placed. In this regard, the parts conforming to these portions may come into contact with a bottom surface in the space **7a** of the hip joint placement region **7** and receive a body pressure unless the hip joint **J2** is pressed.

Modifications

(A) In the embodiment, the placement surface **12a1** of the sacrum support portion **12a** is on a horizontally flat plane, but the invention is not limited thereto. As a modification of the invention, as shown in FIG. 9, the height of the sacrum support portion **12a** may be set to gradually lower as advancing toward the leg of the person **50** in the supine position (as going in the direction of the leg-toward direction **X2**), and the sacrum support portion **12a** may support at least a continuous underside from the part conforming to the sacrum **S** to a part conforming to a lumbar vertebra adjacent to the sacrum **S** of the person **50** in the supine position. In other words, the load on the lumbar vertebrae L3 to L5 connected to the sacrum **S** may be reduced by forming the placement surface **12a1** of the sacrum support portion **12a** into such a sloping shape that it lowers as advancing in the leg-toward direction **X2** and utilizing the sloping shape of the placement surface **12a1**.

This configuration enables the sacrum support portion **12a** to come into broad contact with the parts conforming to the sacrum **S** and the lumbar vertebrae L4 to L5 to support the parts while dispersing the body pressure, when the sacrum **S** nutates forward (in the upward direction **Z1**). Consequently, the load on the lumbar vertebrae L3 to L5 connected to the sacrum **S** can be further reduced.

In other words, as shown in FIG. 9, since the whole of the parts conforming the lumbar vertebrae L4 to L5 and the sacrum **S** are placed on the placement surface **12a1** in the sloping shape, a bending angle between the lumbar vertebrae L3 and L4 at the leg side edge **3a** of the back support portion **3** becomes small. The bending angle between the lumbar vertebrae L3 and L4 in this case is much smaller than that in a case where the sacrum **S** is partially placed on the leg side edge **12a2** of the horizontal placement surface **12a1** as shown in FIG. 8, from which it can be understood that the load on the lumbar vertebrae L3 to L5 is reduced.

(B) In the embodiment, an exemplary mattress **1** that is integrally made of material such as urethane is described, but the invention is not limited thereto. As another modification of the invention in a case that the sacrum adaptation portion **12** includes the sacrum support portion **12a** that supports the part conforming to

12

the sacrum **S** of the person **50** in the supine position and the sacrum support portion **12a** is set to have a height being the same as the height of the ilium support portion **11**, the hardness of the sacrum support portion **12a** may be set to be lower than the hardness of the ilium support portion **11** by changing properties of at least one of the materials of the ilium support portion **11** and the sacrum support portion **12a**.

In this configuration, the sacrum support portion **12a** is softer than the ilium support portion **11**, which enables the sacrum support portion **12a** to support the sacrum **S** so that it can nutate while reducing the reaction force (body pressure) from the sacrum support portion **12a** onto the part conforming to the sacrum **S**. Consequently, the load on the lumbar vertebrae L3 to L5 connected to the sacrum **S** can be reduced.

(C) In the embodiment, the pair of ilium support portions **11** has the respective placement surfaces **11a** on which the parts conforming to the iliac crests **LMa** are placed and the inner upper edge **11b**, which is an edge of the placement surface **11a** closer to the sacrum adaptation portion **12**. The inner upper edge **11b** is angular as shown in FIG. 1. As a modification of the invention, the inner upper edge **11a2** may be beveled to have a planar or round shape.

In this case, since the inner upper edge **11b** is beveled, the body pressure onto the inner upper edge **11b** is dispersed even if the inner upper edge **11b** of the ilium support portion **11** comes into contact with the part conforming to the iliac crest **LMa** in the supine position. Thus, the pain and the discomfort in the supine position can be reduced.

(D) In the embodiment, as an exemplary sacrum adaptation portion **12** arranged between the pair of ilium support portions **11** and located below the sacrum **S**, the sacrum adaptation portion **12** including the sacrum support portion **12a** for supporting the part conforming to the sacrum **S** is described, but the invention is not limited thereto. The invention is required only that: the sacrum adaptation portion **12** be arranged between the pair of ilium support portions **11** and located below the sacrum **S**; and the pair of ilium support portions **11** and the sacrum adaptation portion have such a configuration that the body pressure onto the sacrum adaptation portion onto the part conforming to the sacrum **S** of the person in the supine position is lower than the body pressures from the pair of ilium support portions **11** onto the parts conforming to the pair of ilia **LM** of the person **50** in the supine position.

Thus, as a modification of the invention, the sacrum adaptation portion **12** may entirely include a sacrum non-support portion **12b** that is spaced away from a part conforming to the sacrum **S** of the person in the supine position to render non-support to the part conforming to the sacrum **S**, as shown in FIG. 10. In this configuration, there is no sacrum support portion **12a** that protrudes from the upper surface **2a** of the base portion **2** in the upward direction **Z1**; there is only a sacrum non-support portion **12b** at the same height as the upper surface **2a**. The sacrum non-support portion **12b** and opposite surfaces of the pair of ilium support portions **11** on both sides thereof forms a space **16**.

In this configuration, the sacrum non-support portion **12b**, which is entirely included in the sacrum adaptation portion **12** and is spaced away from the part conforming to the sacrum **S**, renders non-support to the part conforming to the sacrum **S**. Thus, the sacrum **S** is received in the space **16** above the sacrum non-support portion **12b**. This configuration enables supporting the part conforming to the sacrum **S**.

13

so that it can nutate without receiving any effects by the reaction force (body pressure) from the sacrum non-support portion 12b that is included in the sacrum adaptation portion 12. Consequently, the load on the lumbar vertebrae L3 to L5 connected to the sacrum S can be reduced.

(E) In the embodiment, the back support portion 3 is described as an exemplary protrusion portion for supporting the back 52 of the person 50 in the supine position as shown in FIGS. 1 to 5, but the invention is not limited thereto. For example, as a modification of the invention, the back support portion 3 serving as the protrusion portion may be omitted and the upper surface 2a of the base portion 2 may support the back 52, as shown in FIG. 11.

(G) In the mattress 1 in the embodiment, as shown in FIGS. 1 to 5, the back support portion 3, the pelvis support portion 4 (the pair of ilium support portions 11 and the sacrum support portion 12a), and the leg support portion 5 each have a shape of a flat, rectangular, and thick plate, but the invention is not limited thereto, and may be formed to have a curved shape conforming to the body shape of the person 50 in the supine position. Particularly, the portion that supports a part conforming to the sacroiliac joint J1 is preferably formed to have such a shape with a smooth slope or a space that no stress is given onto the part conforming to the sacroiliac joint J1.

Summary of Embodiment

The summary of the embodiment is as follows.

A mattress according to the embodiment for supporting at least a part conforming to a pelvis of a person in a supine position, includes: a pair of ilium support portions arranged below respective parts conforming to at least widthwise outer portions of iliac crests of a pair of ilia of the pelvis for individually supporting parts conforming to the pair of ilia from below; and a sacrum adaptation portion arranged between the pair of ilium support portions and located below a part conforming to a sacrum between the pair of ilia of the pelvis, wherein the pair of ilium support portions and the sacrum adaptation portion have such a configuration that a body pressure onto the sacrum adaptation portion is lower than a body pressure onto the pair of ilium support portions.

The mattress includes the pair of ilium support portions arranged at respective positions below the iliac crests, which are edges closer to the head of the person in the supine position, of the pair of ilia of the pelvis so as to come into contact with the parts conforming to at least the widthwise outer portions of the iliac crests, and the sacrum adaptation portion arranged between the pair of ilium support portions. Thus, the pair of ilium support portions can individually support the parts conforming to the pair of ilia from below with coming into contact with the respective parts conforming to the iliac crests of the pair of ilia, when the person is in the supine position on the mattress having the configuration above. At this time, the pair of ilia receives a reaction force (body pressure) from the ilium support portions on the parts conforming to the iliac crests, which promotes the movement of turning forward and toward the center with respect to the body (i.e., rotating medially).

The pair of ilium support portions and the sacrum adaptation portion of the mattress have such a configuration that the body pressure onto the sacrum adaptation portion is lower than the body pressure onto the pair of ilium support portions. Thus, the sacrum between the pair of ilia can turn forward and toward the leg in accordance with the medial

14

rotation of the pair of ilia, i.e., can nutate, without being obstructed by the reaction force (body pressure) from the sacrum adaptation portion. The nutation of the sacrum causes the diaphragm connected to the lumbar vertebrae 5 continued to the sacrum to move in the direction toward the head of the person in the supine position. This makes the rib cage contract, thereby facilitating the exhalation. When the exhalation is facilitated, the inhalation, which is the counter action thereof, is also facilitated. Consequently, the breathing in the supine position can be promoted.

Preferably, a height of the ilium support portion of the mattress may be greater than a height of the sacrum adaptation portion.

In this configuration, the ilium support portion can reliably support the part conforming to the ilium to promote the medial rotation of the ilium and the nutation of the sacrum, while reducing the reaction force (body pressure) from the sacrum support portion onto the part conforming to the sacrum. Consequently, the breathing in the supine position can be reliably promoted.

Preferably, the pair of ilium support portions of the mattress may have respective placement surfaces on which parts conforming to the iliac crests are placed and an edge 25 of the placement surface closer to the sacrum adaptation portion may be beveled.

In this configuration, since the edge of the ilium support portion closer to the sacrum adaptation portion is beveled, the body pressure onto the edge is dispersed even if the edge 30 comes into contact with the part conforming to the iliac crest in the supine position. Thus, the pain and the discomfort in the supine position can be reduced.

Preferably, the mattress may further include a back support portion that supports a back of the person in the supine 35 position and a height of the back support portion may be the same as the height of the ilium support portion.

In this configuration, the mattress supports the back and the part conforming to the ilium of the person in the supine 40 position on the same plane. Thus, the discomfort due to the ilium support portion protruding upward can be reduced. The ilium support portion is preferably slightly higher than the back support portion to enhance the effect by the ilium support portion of causing the ilium to medially rotate.

Preferably, the sacrum adaptation portion of the mattress 45 may include a sacrum support portion for supporting a portion of the sacrum closer to a head of the person in the supine position, and a sacrum non-support portion spaced away underneath from a portion of the sacrum closer to a leg of the person in the supine position to render non-support to the portion closer to the leg.

In this configuration, the portion of the sacrum closer to the head is located above the portion thereof closer to the leg after the nutation of the sacrum. Therefore, in the configuration above, the sacrum support portion partially supports 55 the portion of the sacrum closer to the head, and the sacrum non-support portion, which is spaced away underneath from the portion closer to the leg, renders non-support to the portion. This enables adjusting the body pressure onto the ilium support portion, the body pressure onto the sacrum support portion, and the body pressure onto the sacrum non-support portion so as to gradually lower one after another in this order. Additionally, it is possible to further lower the average body pressure onto the sacrum from the whole of the sacrum adaptation portion with keeping the sacrum tilting forward. This can promote a smooth nutation 60 of the sacrum. Consequently, the breathing in the supine position can be more reliably promoted.

15

Preferably, the height of the sacrum support portion of the mattress may be made to gradually lower as advancing toward the leg of the person in the supine position, and the sacrum support portion may support at least a continuous underside from the part conforming to the portion of the sacrum closer to the head of the person to a part conforming to a lumbar vertebra adjacent to the sacrum of the person in the supine position. 5

This configuration enables the sacrum support portion to come into broad contact with the parts conforming to the sacrum and the lumbar vertebra to support the parts while dispersing the body pressure, when the sacrum nutates forward. Consequently, the load on the lumbar vertebrae connected to the sacrum can be further reduced. 10

Preferably, the sacrum adaptation portion of the mattress may include a sacrum support portion that supports a part conforming to the sacrum of the person in the supine position, and the sacrum support portion may have a height being the same as a height of the ilium support portion and a hardness lower than a hardness of the ilium support portion. 15 20

In this configuration, the sacrum support portion is softer than the ilium support portion, which enables the sacrum support portion to support the sacrum so that it can nutate while reducing the reaction force (body pressure) from the sacrum support portion onto the sacrum. Consequently, the load on the lumbar vertebrae connected to the sacrum can be reduced. 25

Preferably, the mattress may include a sacrum non-support portion that is spaced away from a part conforming to the sacrum of the person in the supine position to render non-support to the sacrum. 30

This configuration enables supporting the sacrum so that it can nutate without receiving any effects by the reaction force (body pressure) from the sacrum non-support portion that is included in the sacrum adaptation portion. Consequently, the load on the lumbar vertebrae connected to the sacrum can be reduced. 35

The mattress in the embodiment having the configuration above can promote the breathing in the supine position. 40

The invention claimed is:

1. A mattress for supporting at least a part corresponding to a pelvis of a person's body in a supine position, comprising: 45

a pair of ilium support portions arranged below respective parts corresponding to at least widthwise outer portions of iliac crests of a pair of ilia of the pelvis for individually supporting parts corresponding to the pair of ilia of a person's body from below; and 50

a sacrum adaptation portion arranged between the pair of ilium support portions of the mattress and located below a part corresponding to a sacrum between the pair of ilia of the pelvis of a person's body, wherein the pair of ilium support portions and the sacrum adaptation portion have such a configuration that a body pressure onto the sacrum adaptation portion is lower than a body pressure onto the pair of ilium support portions, and 55

a height of the ilium support portion is greater than a height of the sacrum adaptation portion, and the sacrum adaptation portion includes:

a sacrum support portion having a height lower than the height of the ilium support portion for supporting a part corresponding to a portion of the sacrum closer to a head of the person in the supine position, and a sacrum non-support portion having a height lower than the height of the sacrum support portion of the mattress and spaced away underneath from a portion of the sacrum closer to a leg of the person's body in the supine position to render non-support to a part corresponding to the portion closer to the leg, wherein the sacrum support portion and the sacrum non-support portion are aligned with each other along the longitudinal direction of the mattress. 10

2. The mattress according to claim 1, wherein the height of the sacrum support portion of the mattress gradually lowers as advancing toward the leg of the person's body in the supine position, and the sacrum support portion supports at least a continuous underside from the part of the person's body corresponding to the portion of the sacrum closer to the head of the person to a part corresponding to a lumbar vertebra adjacent to the sacrum of the person's body in the supine position. 15 20

3. The mattress according to claim 1, further comprising: a back support portion that supports a back of the person's body in the supine position, wherein a height of the back support portion is the same as the height of the ilium support portion. 25

4. A mattress for supporting at least a part corresponding to a pelvis of a person's body in a supine position, comprising:

a pair of ilium support portions arranged below respective parts corresponding to at least widthwise outer portions of iliac crests of a pair of ilia of the pelvis for individually supporting parts corresponding to the pair of ilia of a person's body from below; and 30

a sacrum adaptation portion arranged between the pair of ilium support portions of the mattress and located below a part corresponding to a sacrum between the pair of ilia of the pelvis, of the person's body wherein the pair of ilium support portions and the sacrum adaptation portion have such a configuration that a body pressure onto the sacrum adaptation portion is lower than a body pressure onto the pair of ilium support portions, and 35

the sacrum adaptation portion includes a sacrum support portion that supports a part corresponding to the sacrum of the person's body in the supine position, and the sacrum support portion has a height being the same as a height of the ilium support portion and a hardness lower than a hardness of the ilium support portion, wherein 40

the pair of ilium support portions and the sacrum support portion are aligned with each other along the width direction of the mattress. 45

* * * * *
